(57) **CLAIM**

The ornamental design for a demolition tool, as shown and described.

DESCRIPTION

FIG. 1 is a perspective view of a demolition tool, showing our new design;

FIG. 2 is a front view thereof;

FIG. 3 is a right-side view thereof;

FIG. 4 is a back view thereof;

FIG. 5 is a left side view thereof;

FIG. 6 is a bottom view thereof; and,

FIG. 7 is a top view thereof.

The broken lines depict portions of the demolition tool in which the design is embodied that are not considered part of the claimed design.
